UNITED STATES PATENT OFFICE.

JOHN G. HARRINGTON, OF STREATOR, ILLINOIS.

FRUIT-BOTTLE HOLDER.

SPECIFICATION forming part of Letters Patent No. 716,226, dated December 16, 1902.

Application filed September 25, 1901. Serial No. 76,499. (No model.)

To all whom it may concern:

Be it known that I, JOHN G. HARRINGTON, a citizen of the United States, residing at Streator, in the county of Lasalle and State of Illinois, have invented certain new and useful Improvements in Fruit-Bottle Holders; and I do hereby declare that the following is a full, clear, and exact description of the invention, which will enable others skilled in the art to which it appertains to make and use the same.

This invention relates to a fruit-can holder.

The object of my invention is to provide an inexpensive holder or gripping arrangement for fruit-bottles and one that will hold the bottle firmly after being set and locked.

A further object is to provide a holder which will hold large or small bottles with the same ease.

Another object is to provide a holder for fruit-bottles which will lock automatically after being tightened on the bottle.

In the accompanying drawings, Figure 1 is a perspective view of the holder as viewed from the rear. Fig. 2 is a perspective view of the same as viewed from the front and showing a bottle held therein. Fig. 3 is a view of the locking arrangement for the holder.

A indicates a support for the bottle, which consists of a bracket which may be firmly attached to the wall or table or other convenient object. Said bracket has a depression B, in which the bottle rests. Erected at the front of the bracket is a block C, which carries a metal strip D by means of screws. The ends 35 of the latter project beyond said block C, and a pin E passes through a hole at one end of said strip D into a hole in the bracket A just beneath and has a metal bushing F. A metal band G, having an overturned end to form 40 an eye, is held by the said pin E, as shown in the figures. The other end of said band is similarly constructed, and a pin H passes through it, and each end of said pin is carried in a loop or eye I of a lever J. This is 45 constructed as in Fig. 3, in which the pin H is shown as set away from the pivotal extremities of the lever, one of such extremities being carried in the strip D and the other in a hole K in the bracket A. Now it will be 50 seen that if the lever J is swung to its limit in either direction the end of the band G will

describe an arc of a circle about the ends of said lever where carried in the strip D and bracket A. This being true, if a bottle be set upon the bracket and the lever thrown 55 to a position to cause the band G to grip the bottle the end thereof held by the pin H will be drawn forward to the limit of movement, and then by throwing the lever beyond the center the pin H will pass behind the piv- 60 oted point of the lever, where it will remain under tension until released by a reversed movement.

I have constructed the device so that bottles of any size may be accommodated. This 65 I accomplish by providing at several points a loop or eye L, so that if large bottles are employed the device is used in the position shown; but for smaller bottles the pin E is removed and one of the loops L is placed beneath it and held thereby as before. This 70 adjustable feature is a very important part of my device and will be so recognized.

I find that bottles, although made to hold a stated amount of fruit, are quite apt to be variable in size, being overlarge. This happens in forming the bottle, and no two are of the same size or roundness. The consequence of this is that the band G cannot always be locked, if too large, by means of the lever J. 75 To provide means for locking for each bottle, I have made use of a notched strip J', pivoted to the block C. When the lever J is prevented from going far enough to be locked, the strip J' is thrown down to engage the said lever by 80 one of the notches. The bottle will thus be held in a firm manner, as will be understood.

Having thus described my invention, I claim—

1. A fruit-bottle holder comprising a support A for the bottle and said holder, the block C mounted thereon, a strip D secured on the top of said block, a pin E in said strip D and socketed in the support A and removable therefrom, the band G, a series of loops L on a portion thereof through any one of which the said pin E is adapted to pass to hold said band and by which the band is made adjustable for length for various-sized bottles, the lever J pivoted between the strip D and the support A and having the opposite end of the band G attached thereto, substantially as

shown with reference to the pivot thereof, all being arranged substantially as shown and described.

2. A fruit-bottle holder comprising the support A, the flexible band G supported above the same and held at one end, the other end being movable to tighten the said band upon the bottle, a lever to which said movable end is secured, said lever arranged whereby by movement thereof the band may be tightened upon the bottle and locked, and a notched

plate pivoted in the region of the lever and adapted for engagement therewith whereby said lever may be locked when the bottle is of abnormal size which would prevent the locking ordinarily.

In testimony whereof I affix my signature in presence of two witnesses.

JOHN G. HARRINGTON.
